HOSE SUPPORTING CLASP

George A. Gruss, Bridgeport, Conn.

Application February 5, 1945, Serial No. 576,225

11 Claims. (Cl. 24—252)

1

This invention relates to grips and more particularly to garter grips used for supporting stockings.

The present button type of garter grip is objectionable because the button protrudes above the stocking and may be easily detected when a garment fits snugly over the button. It is further objectionable because it grips the stocking by a narrow portion which causes runs in the stocking. A further objection is that it requires both hands of the user to attach or detach the grip from the stocking.

The object of my invention is to provide a garter grip which will not protrude nor show through a skirt, which will grip a wide portion of the stocking and thereby prevent runs, which may be readily attached to and detached from the stocking with one hand.

These objects and other advantageous ends will be clearly set forth by the accompanying drawing and the following description of same in which:

Figure 1 is a plan view of a garter grip made in accordance with my invention, showing it attached to a portion of a stocking.

Figure 2 a side view of Figure 1, viewed from the direction of the arrows on line 2—2, showing the stocking in section.

Figure 3 is a sectional view taken on line 3—3 of Figure 1.

Figure 4 a view similar to Figure 3 showing the grip in open position.

Figure 5 a sectional view taken on line 5—5 of Figure 1.

Figure 6 an enlarged fragmentary sectional view of the resilient pivotal means shown in Figure 3, illustrating the action of the grip; and

Figure 7 a perspective view of a spring used in the resilient pivotal means.

Referring to the drawings, the grip comprises a frame 1, a clamping member 2, an enclosure 3 swingably connected to the frame and clamping member and a pair of springs 4 positioned back to back within the enclosure and acting against the pivotal parts of the frame and clamping member to keep them against the walls of the enclosure.

The frame is made from sheet metal and bent to provide an upturned or U-shaped stocking support 5 of such width as will prevent stocking runs under strains of ordinary use. The edge 6 of the support is curved and converges into the edges of stocking support bottom 7 and thereby tends to distribute the stocking strain evenly over the entire edge of the support. Side bars 8 ex-

2

tend upward from support 5 and terminate in V-shaped bends 9. Pivots 10 project inward from the upper legs of each bend 9 and are disposed within enclosure 3 and surrounded by its end wall 11, side walls 12 and one end 13 of springs 4, as shown in Figures 4 and 6.

A second pair of pivots 14 project inwardly from bent fingers 15 at the upper parts of clamping member 2. These pivots are confined within 10 enclosure 3 and surrounded by its end wall 16, side walls 12 and the other end 17 of springs 4.

Each spring 4 is made from strip material bent into the shape shown in Figure 7. The ends 13 and 17 of each spring act upon the pivots 10 and 14 respectively and receive their spring action from the oblong loop 18. If desired the center of the back of the spring may be offset slightly inwardly as at 19 to insure that the backs of the springs will abut each other at points 20 substantially in line with spring ends 13 and 17. The springs are mounted between the two frame pivots 10 and the two clamping member pivots 14 and within enclosure 3. The side walls 12 of the enclosure slidably fit springs 4 and thus allow them free resilient action against the pivots 10 and 14.

The clamping member is shaped to provide a depression 21 disposed centrally between and spaced from side bars 8 of the frame as shown in Figure 5. This depression provides a large surface for finger contact when pushing the clamping member outward to the open position shown in Figure 4.

Flanges 22 at each side of the depression are spaced from the side bars 8 to allow several stocking folds or thicknesses to form during attaching or wearing of the grip without affecting the full closing of the grip in the position shown in Figures 3 and 5.

A clamping edge 23 emerges from depression 21 and flanges 22 and is adapted to clamp the stocking 24 in U-shaped stocking support 5.

The frame may be provided with any suitable elastic fastening means. I have shown such means in the form of a slot 25 through which an elastic 26 passes and then folds around a bar 27. The elastic may be sewed as at 28 to secure the grip thereto.

To attach the grip to the stocking, the grip is held in one hand in the open position shown in 50 Figure 4. The U-shaped stocking support 5 is then slipped under the edge of the stocking, and the enclosure 3 together with the clamping member 2 are pressed with the finger toward the frame to swing them to the closed position shown in 55 Figure 3, thus gripping the stocking between the

clamping edge 23 and the bottom 1 of the stocking support. Gripping pressure is produced by the toggle action of enclosure 3 and clamping member 2, forcing pivots 10 and 14 toward each other against the action of springs 4, as illustrated in dot and dash and full line positions in Figure 6.

The swinging movement of enclosure 3 and clamping member 2 is stopped in the fully closed position by the pivot edges 29 abutting side walls 12 of the enclosure. The angle at which pivots 10 and 14 engage sidewalls 12 may be varied to suit different requirements. In the present instance the angle found most suitable for a clear description is 45 degrees. It permits a 90 degree swing of enclosure 3 on frame pivots 10 and a 90 degree swing of clamping member 2 on its pivots 14. The 90 degree swing is the amount required from open to closed position.

Springs 4, in addition to maintaining gripping pressure on clamping member 2, also tend to keep enclosure 3 in closed position.

This action is due to the relation of the adjacent edges 29 of pivots 10 and 14 acting on springs 4 at opposite side walls 12 of the enclosure. This relation of pivot edges 29 tends to swing the enclosure in a direction toward closed position. The frictional resistance of pivot edges 29 sliding on the spring ends 13 and 17 also tend to prevent accidental opening of the grip.

To detach the grip from the stocking the finger of the hand is pressed on the underside of enclosure 3 or depression 21 to force it away from the frame to the open position. When enclosure 3 and clamping member 2 have passed the 45 degree dot and dash position 30 of Figure 6, springs 4 will force them to the fully open position. In this position the pivot edges 29 will have moved to abut the opposite walls 12 of the enclosure, thus stopping and keeping enclosure 3 and clamping member 2 in open position. The frame with the stocking support 3 may then be slipped from under the stocking edge.

In case of accidental stepping on the grip while dressing or undressing, the force of the step would merely close the grip and no harm would be done. This will be apparent when it is seen that the clamping member pivots 14 abut the walls of the enclosure when the clamping member is swung toward the frame, thus carrying the enclosure with it to follow the dot and dash line positions of Figure 6 to the fully closed position.

Various thicknesses of stocking may be gripped between the stocking support 5 and the clamping member due to the pivots 10 and 14 having springs 4 between them. It should be understood that other resilient means equivalent in function to springs 4 may be used between pivots 10 and 14.

While I have set forth my invention in a particular form, it will be understood that its shape may be changed without affecting the function thereof, and hence I do not limit myself to the precise construction set forth, but consider it my liberty to make such changes and alterations as fairly come within the scope of the appended claims.

Having thus described my invention, what I claim as new and desire to secure by Letters Patent is:

1. A grip comprising a frame having an upturned stocking support at one end and pivotal means adjacent the other end; a clamping member having one end adapted for clamping material in the stocking support and pivotal means at the other end; an enclosure surrounding both mentioned pivotal means and providing a space be-

tween them in which they move toward each other; and resilient means mounted within the enclosure in said space and engaging said pivotal means to apply pressure thereon; the enclosure and resilient means forming confines in which the pivotal means may swing and move toward each other against the action of said resilient means, the enclosure and clamping member acting as a toggle to clamp material in the stocking support when swung to closed position.

2. A grip comprising a frame having an upturned stocking support at one end and pivotal means adjacent the other end; a clamping member having one end adapted for clamping material in the stocking support and pivotal means at the other end; an enclosure surrounding both mentioned pivotal means and providing a space between them in which they move toward each other; and springs mounted within the enclosure in said space and engaging said pivotal means to apply pressure thereon; the enclosure and springs forming confines in which the pivotal means may swing and move toward each other against the action of said springs, the enclosure and clamping member acting as a toggle to clamp material in the stocking support when swung to closed position.

3. A grip comprising a frame having an upturned stocking support at one end and pivotal means adjacent the other end; a clamping member having one end adapted for clamping material in the stocking support and pivotal means at the other end; an enclosure surrounding both mentioned pivotal means and providing a space between them in which they move toward each other; and springs of strip material mounted within the enclosure in said space and engaging said pivotal means to apply pressure thereon; the enclosure and springs forming confines in which the pivotal means may swing and move toward each other against the action of said springs, the enclosure and clamping member acting as a toggle to clamp material in the stocking support when swung to closed position.

4. A grip comprising a frame of sheet material having an upturned stocking support at one end and pivots adjacent the other end; a clamping member of sheet material having one end adapted for clamping material in the stocking support and pivots at the other end; an enclosure surrounding both mentioned pivots and providing a space between them; and resilient means mounted within the enclosure in said space and engaging the adjacent edges of said pivots to apply pressure thereon; the enclosure and resilient means forming bearings in which the pivots may swing and slide toward each other against the action of said resilient means, the enclosure and clamping member acting as a toggle to clamp material in the stocking support when swung to closed position.

5. A grip comprising a frame of sheet material having an upturned stocking support at one end and pivots adjacent the other end; a clamping member of sheet material having one end adapted for clamping material in the stocking support and pivots at the other end; an enclosure having side and end walls surrounding both mentioned pivots and providing a space between them; and strip springs slidably mounted between the side walls of the enclosure in said space and engaging the edges of said pivots to apply pressure thereon, the side and end walls of the enclosure and the springs forming bearings in which the pivots may swing and slide toward each other

against the action of the springs, the enclosure and clamping member acting as a toggle to clamp material in the stocking support when swung to closed position.

6. A grip comprising a frame having a stocking support at one end and inwardly extending pivot lugs adjacent the other end; a clamping member having one end adapted for clamping material in the stocking support and inwardly extending pivot lugs at the other end; an enclosure having side walls and end walls surrounding both mentioned pivot lugs; and a pair of strip springs slidably mounted between the side walls of the enclosure and disposed between the pivot lugs, each spring being shaped into an oblong loop, the inner side of the loops abutting each other and the outer sides having outwardly bent ends engaging the adjacent edges of the pivot lugs, the springs and the side and end walls of the enclosure forming bearings in which the adjacent edges of the pivot lugs swing to the opposite side wall and slide toward each other against the action of the springs, the enclosure and clamping member acting as a toggle to clamp material in the stocking support.

7. A grip comprising a frame having a stocking support at one end and inwardly extending pivot lugs adjacent the other end; a clamping member having one end adapted for clamping material in the stocking support and inwardly extending pivot lugs at the other end; an enclosure having side walls and end walls surrounding both mentioned pivot lugs, one edge of the pivot lugs of the frame engaging one side wall and the adjacent edge of the pivot lugs of the clamping member engaging the opposite side wall when in fully opened or closed position; and a pair of strip springs slidably mounted between the side walls of the enclosure and disposed between the pivot lugs, each spring being shaped into an oblong loop, the inner side of the loops abutting each other and the outer sides having outwardly bent ends engaging the adjacent edges of the pivot lugs, the springs and the side and end walls of the enclosure forming bearings in which the adjacent edges of the pivot lugs swing to the opposite side wall and slide toward each other against the action of the springs, the enclosure and clamping member acting as a toggle to clamp material in the stocking support.

8. A grip comprising a frame having inwardly extending pivot lugs adjacent one end and a support at the other end; a clamping member having inwardly extending pivot lugs at one end and the other end adapted to clamp material in the support; an enclosure surrounding both mentioned pivot lugs; and a pair of strip springs mounted in the enclosure and having oblong loops abutting each other at their inner sides, the outer sides of the spring loops having outwardly bent ends engaging the edges of the pivot lugs, the enclosure and springs forming bearings for the pivot lugs to swing and slide toward each other against the action of the springs, the enclosure and clamping member acting as a toggle to clamp material in the support when swung to closed position.

9. A grip comprising a frame having pivots with offset edges adjacent one end and a support

at the other end; a clamping member having pivots with offset edges at one end and the other end adapted to clamp material in the support; an enclosure having side and end walls surrounding both mentioned pivots, one side wall engaging the offset edges of the frame pivots and the other side wall engaging the offset edges of the clamping member pivots; and springs mounted between the side walls of the enclosure and engaging the offset edges of the pivots; the side and end walls of the enclosure and the springs forming confines in which the offset pivot edges move from one side wall to the other and also toward each other against the action of the springs when the enclosure and clamping member are swung to closed position.

10. A grip comprising a frame having offset pivots adjacent one end and a support at the other end; a clamping member having offset pivots at one end and the other end adapted to clamp material in the support; an enclosure having side and end walls surrounding both mentioned offset pivots, one side wall engaging one edge of both offset pivots and the other side wall engaging the other edge of said both offset pivots; and springs mounted between the side walls of the enclosure and engaging the adjacent edges of said offset pivots, the side and end walls of the enclosure and the springs forming confines in which the offset pivot edges move from one side wall to the other against the action of the springs when the enclosure and clamping member are swung to closed position.

11. A grip comprising a frame of sheet material having pivot lugs offset at an angle thereto adjacent one end and a support at the other end; a clamping member of sheet material having pivot lugs offset at an angle thereto at one end thereof and the other end adapted to clamp material in the support; an enclosure having side and end walls surrounding both mentioned pivot lugs, one side wall engaging one edge of both mentioned pivot lugs and the other side wall engaging the opposite edge of said pivot lugs; and a pair of springs mounted between the side walls of the enclosure and having oblong loops abutting each other at their inner sides, the outer sides of the spring loops having outwardly bent ends engaging the adjacent edges of said pivot lugs, the side and end walls of the enclosure and the spring ends forming bearings in which the pivot lug edges move from one side wall to the other and also toward each other against the action of the springs when the enclosure and clamping member is swung to closed position.
